CLAIM

The ornamental design for a battery box for a truck, as shown and described.

DESCRIPTION

FIG. 1 is an isometric view of a battery box for a truck, showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

Stippling in the drawings represents the three-dimensional contours of the design, and is not intended to indicate surface decoration. The broken lines shown in the drawings depict portions of the battery box for a truck that form no part of the claimed design.
